(No Model.)

H. MENKE, Jr.
REVOLVING FAN.

No. 337,600.

Patented Mar. 9, 1886.

UNITED STATES PATENT OFFICE

HENRY MENKE, JR., OF DE WITT, NEBRASKA.

REVOLVING FAN.

SPECIFICATION forming part of Letters Patent No. 337,600, dated March 9, 1886.

Application filed November 14, 1885. Serial No. 182,669. (No model.)

To all whom it may concern:

Be it known that I, HENRY MENKE, Jr., of De Witt, in the county of Saline and State of Nebraska, have invented a new and Improved Revolving Fan, of which the following is a full, clear, and exact description.

My invention relates to revolving fans adapted for use on dining or library tables, or at other places, for driving away flying insects, and for briskly circulating the air for cooling persons near the machine; and the invention has for its object to provide a simple, inexpensive, and effective device of this character.

15 The invention consists in certain novel features of construction and combinations of parts of the revolving fan, all as hereinafter fully set forth.

Reference is to be had to the accompanying drawings, forming part of this specification, in which similar letters of reference indicate corresponding parts in all the figures.

Figure 1 is a side view of the fan with the frame in vertical section, and the base and driving-gearing in section on the line xx , Fig. 2. Fig. 2 is a plan view of the base with its cover removed to show the driving-gearing. Fig. 3 is an enlarged view of the driving-gearing removed from the base and as 30 viewed in the direction of the arrow 1 in Fig. 2; and Fig. 4 is a side elevation of the case, showing, also, a preferred arrangement of spring-winding mechanism.

To spindles A A, which are journaled at 35 opposite sides of the frame B of the driving-gearing, are secured the one ends of coiled springs C C, the other ends of which are secured to posts c c of the frame B, and on the spindles A A are placed loosely the cog-wheels D D, over which are fixed to the spindles the ratchets E E, which are engaged by the spring-pressed pawls e e, which are pivoted to the cog-wheels D D, and so that while the wound springs are unwinding in the same 45 direction the wheels D D will be rotated in like direction.

Each of the wheels D gears with a pinion, f, fast on a shaft, F, journaled in the frame B, and to which shaft also is fixed a cog-wheel, 50 G. The two cog-wheels G G, which rotate in the same direction, mesh with a pinion, H,

which stands between them, and is fast on a shaft, I, to which is fixed a cog-wheel, J, which in turn meshes with a pinion, K, fast on the driving-shaft L, to which the shaft M 55 of the revolving fans N N is connected. The power of both the springs C C thus is utilized to rotate the fans. By using two springs they may each be made lighter than a single spring which will rotate the fans for any given time, 60 and consequently the springs C C may be more easily wound up than could be a single heavy spring.

The driving-gearing is secured within a case, O, which forms the base or support to 65 the fans, and to the top of the base O are attached a number of inclined uprights, o, having a cap plate or piece, o', in which the fan-shaft M has a bearing. (See Fig. 1.)

To the fan-shaft M is attached a head-piece, 70 m, to which are pivoted the inner ends of the rods P P, which are entered through eyes or staples p p on the handles n n of the fans N N, and whereby the fans may be slid along the rods P P to set them nearer to or farther from 75 the shaft M, to give them any desired sweep or range horizontally as they are revolving, and the rods P P are pivotally connected by rods R R with a runner or block, S, fitted to slide on the fan-shaft M, and provided with a 80 set-screw, s, whereby the runner may be fixed to the shaft M at any desired height on the shaft for holding the fans N N higher or lower, as may be necessary or desirable, to cause the revolving fans to clear higher or lower objects 85 on the dining or library table on which the machine stands, or to direct the air-currents from the fans to the best advantage for cooling persons near the fan.

The springs C may be wound up or put in 90 tension by applying a key to the vertical spring-spindles A A; but I prefer to fix to each of the spindles a bevel-pinion, a, which meshes with a bevel-pinion, a', on a horizontal shaft, A', journaled in lugs on the case, 95 and whereby the springs may be wound more conveniently by applying the key to the outer ends of the shafts A', as will be understood from Fig. 4 of the drawings.

Having thus described my invention, what I claim as new, and desire to secure by Letters Patent, is—

In revolving fans, the combination, with a base or support and the fan shaft M, of driving-gearing consisting of two springs, C C, cog-wheels D D, adapted to be rotated in the same direction by the springs, pinions f f, meshing with wheels D D, cog-wheels G G on the shafts of pinions f f, a pinion, H, rotated by the wheels G G, a cog-wheel, I, on the

shaft of pinion H, and a pinion, K, on the driving-shaft L, to which the fan-shaft is attached, substantially as herein set forth.

HENRY MENKE, JR.
